(57) CLAIM

The ornamental design for a tentacle animal bionic lamp, as shown and described.

DESCRIPTION

FIG. 1 is a perspective view of a tentacle animal bionic lamp showing the inventive design.

FIG. 2 is a second perspective view of said tentacle animal bionic lamp showing the inventive design.

FIG. 3 is a front view of said tentacle animal bionic lamp showing the inventive design.

FIG. 4 is a rear view of said tentacle animal bionic lamp showing the inventive design.

FIG. 5 is a left side view of said tentacle animal bionic lamp showing the inventive design.

FIG. 6 is a right side view of said tentacle animal bionic lamp showing the inventive design.

FIG. 7 is a top view of said tentacle animal bionic lamp showing the inventive design.

FIG. 8 is a bottom view of said tentacle animal bionic lamp showing the inventive design; and,

FIG. 9 is a perspective view of said tentacle animal bionic lamp showing the inventive design in context with a stand support.

The broken lines depict portions of the article and stand support that form no part of the inventive design.
